EASY THREADING NEEDLE

Carl J. Currier, Elmira, N. Y., assignor of one-half to Howard H. Clute, Elmira, N. Y.

Application June 2, 1949, Serial No. 96,759

3 Claims. (Cl. 223—102)

1.

My invention is a novel needle head having an angularly shaped eye, communicating with a slot formed between a tongue at one side of the needle head, formed integrally therewith, to guide the thread when inserted through the slot into the eye, said eye being also shaped to lock the thread after same has been inserted within the eye; the said tongue normally being positioned against the body of the needle head and being shaped to prevent the cloth or fiber from catching or tearing when the needle is passing through the fabric or other material in the act of sewing.

The main object of my invention is to provide a needle that will grip the thread in such manner that it may be securely gripped within approximately one-half inch of the end thereof, by having the upper end of the eye shaped to pinch the sides of the thread without cutting same; the said eye being shaped to grip various sizes of threads, yarns, or other cords.

Another object of the invention is to provide a needle that is very advantageous and practical in the use of surgery, same having the special advantages of permitting different stitches to be made due to the open end of the eye, said eye having one end narrower than the other end, i. e. the roof of the eye of the needle in one type is of a wide range and the opposite end of the eye having a narrower gauge; also to provide a needle in which the narrow and wider ends of the eye are reversed in a machine type needle. For use in surgery the eye would have one side making easy and quick outlets of the eye for removing a loop of thread without disturbing the ends; also in event the needle is to be re-threaded into a loop the slot will allow a quick and easy method of assembling the loop within the eye, at the same time giving the eye a locking action on the thread.

Another object of my invention is to provide a needle having a threading slot that can be threaded in a few seconds by a blind person with ease and with very little guidance; the said needle being provided with an upper end having a blunt portion extending slightly above the upper end of a tongue on the opposite side of the threading slot; the blunt portion being of curved shape disposed oppositely to a curved portion at the outer end of the tongue.

Another object of my invention is to provide a needle that preserves strength to the needle eye where it is most needed, without enlarging the head of the needle.

Other objects of the invention are to provide

5 a needle that will not become unthreaded when dropped; the falling impact of the needle tightening the grip on the thread within the eye, also to provide a needle with the above grip, and at the same time permitting release of the threads or cords with ease, quickness, and without harming the material within the eye.

I will explain my invention with reference to the accompanying drawing, which illustrates several practical embodiments thereof to enable others familiar with the art to adopt and use same; and will summarize in the claims, the novel features of construction, for which protection is desired.

15 In said drawings:

Figure 1 is a side elevation of one embodiment of my needle.

Fig. 2 is a transverse section on the line 2—2, Fig. 1.

20 Fig. 3 is a transverse section on the line 3—3, Fig. 1.

Fig. 4 is a transverse section on the line 4—4, Fig. 1.

Fig. 5 is an enlarged view of Fig. 2.

25 Fig. 6 is the vertical section through the needle, on line 6—6, Fig. 1.

Fig. 7 is an enlarged side elevation of the head of the needle showing the tongue in normal position.

30 Fig. 8 is a view similar to Fig. 7, but showing a thread being forced through the slot.

Fig. 9 is a section through a modified form of needle.

Fig. 10 is a section through a further modified form of needle.

35 Fig. 11 is a section through a still further modified form of needle.

As shown in Figs. 1-8 inclusive, my novel needle comprises an elongated body 1 of metallic or plastic material of oval cross-section, having a pointed lower end 1e. An eye 1a is provided adjacent the opposite end thereof, said eye having a semi-circular lower end and having upwardly converging side walls 1d which substantially

40 meet at the upper end of the eye. As shown, the side walls 1d and lower end of the eye 1a are beveled as at 16 at opposite sides of the eye 1a to reduce the thickness of the opposed side walls, so as to grip by wedging action the thread 2 inserted into the eye 1a when the thread is moved upwardly within the eye, the edges 1b being preferably polished to prevent injury to the thread 2.

45 A slot 1c is provided in the said opposite end 50 of the needle, extending longitudinally of the nee-

dle, with its lower end opening into the lower wider portion of eye $1a$ at one side thereof, and its upper end opening through the upper end of the needle, thereby providing a tongue $1m$ which may be flexed laterally outwardly at its lower end $1r$ when a thread is passing through slot $1c$ into eye $1a$, as shown in Fig. 8, the tongue $1m$ normally lying beside the adjacent portion of the needle body, as shown in Fig. 7.

As shown in Fig. 7, the upper end of the needle body is relatively blunt but is curved slightly downwardly as at $1g$ from its outer edge towards the upper end of slot $1c$, while the upper end of tongue $1m$ slopes oppositely as at $1n$, to form with the portion $1g$ a shallow V-shaped groove at the upper end of slot $1c$ to facilitate entry of thread 2 into the slot $1c$, particularly when the needle is to be threaded by a blind person, or one having poor eyesight, or when being threaded under bad lighting conditions.

Instead of having an oval cross-section, the needle body 1 may be of substantially diamond-shaped cross-section, as shown at $1x$ in Fig. 9; or may be of circular cross-section, as shown at $1y$ in Fig. 10, the eye $1a$ and slot $1c$ however being similar to those previously described; also instead of the side of the eye $1a$ having beveled walls as shown in Figs. 1-10 inclusive, the walls of the eye $1a$ may be rounded, as shown at $1z$ in Fig. 11.

My needle is so designed that the side walls of the eye $1a$ will grip the thread 2 in such manner that the thread may be secured to the needle approximately within one-half inch from its end, the walls pinching opposite sides of the thread without cutting same, and the eye $1a$ being shaped to grip various sizes of threads, yarns, and cords.

I do not limit my invention to the exact forms shown in the drawing, for obviously changes may be made therein within the scope of the claims.

I claim:

1. A needle comprising an elongated body hav-

ing one end pointed; an eye adjacent the opposite end of the body relatively wide at its lower end and having upwardly converging side walls adapted to grip a thread inserted into the eye and shifted upwardly; said eye being centered axially of the needle body, said body having a slot in said opposite end extending longitudinally thereof with its lower end communicating with the lower end portion of the eye, and the upper end of said slot extending through said opposite end of the body, thereby forming a tongue normally contacting the adjacent portion of the needle body throughout its length and adapted to be flexed laterally when a thread is being passed through the slot into the eye.

2. In a needle as set forth in claim 1, the walls of the eye at opposite sides thereof being beveled to reduce the effective width thereof.
3. In a needle as set forth in claim 1, the walls of the eye at opposite sides thereof being rounded to reduce the effective width thereof.

CARL J. CURRIER.
